UNITED STATES PATENT OFFICE.

CHARLES BRAND OFFICER, OF CHICAGO, ILLINOIS, ASSIGNOR TO SULLIVAN MACHINERY COMPANY, A CORPORATION OF MASSACHUSETTS.

AIR-LIFT PUMPING MECHANISM.

Application filed May 19, 1923. Serial No. 640,027.

To all whom it may concern:

Be it known that I, CHARLES B. OFFICER, a citizen of the United States, residing at Chicago, in the county of Cook and State 5 of Illinois, have invented certain new and useful Improvements in Air-Lift Pumping Mechanisms, of which the following is a full, clear, and exact specification.

My invention relates to air lift pumping 10 mechanisms, and more particularly to automatic controlling means for such mechanisms.

An object of my invention is to provide an improved air lift mechanism. Another 15 object of my invention is to provide an improved controlling means for air lift pumping mechanisms. A further object of my invention is to provide an improved automatic controlling means for air lift pumping 20 mechanism adapted to regulate the operation of such a mechanism in accordance with the hydrostatic head in a chamber from which the liquid is being pumped. Other objects and advantages of my invention 25 will hereinafter more fully appear.

In the accompanying drawings I have shown for purposes of illustration one form which my invention may assume in practice.

In these drawings,—

30 Fig. 1 is a view in elevation and diagrammatic in its nature of a pumping system embodying the illustrative form of my invention.

Fig. 2 is a detail on a central vertical 35 plane, showing the controlling mechanism per se.

In the form of my invention which I have shown in the accompanying drawings for the purpose of illustrating the same, there 40 is provided a compressor 1 which discharges by way of a pipe 2 to a receiver 3. This receiver has a connection 4 under control of mechanism generally designated 5 with a down pipe 6 which leads to the foot piece 45 7 of an air lift pumping mechanism whose riser pipe is indicated by 8. The air lift pumping mechanism is adapted to raise liquid from any variety of chamber, but is herein shown as lifting liquid from a sump 50 or well 10.

For the purpose of controlling the supply of air to the foot piece 7 so that the liquid shall not stand too high in the chamber 10, the automatic mechanism 5 is employed. This mechanism comprises a cham-

ber forming casing 11 which is divided into two parts by a partition 12, the partition having herein cast as a part thereof a valve chamber 13. The partition divides the interior of the casing 11 into two parts, the 60 part 14 communicating with the receiver by way of the pipe line 4 and the part 15 communicating with the down pipe 6. A valve 16 is reciprocable in the chamber 13 and is herein shown as having a conical 65 lower extremity 17 adapted to cooperate with a conical seat 18 for the purpose of closing communication between the chambers 14 and 15. It will be observed that the valve casing 13 is perforated in the portion 70 of its wall which projects into the space 15 by a series of openings 20, 21 and 22, although more or less of these may be employed, as may be desirable under the operating conditions encountered. It will 75 further be noted that the valve is traversed by a right angle bleeder passage 23 so arranged that when the valve is closed air may find its way in very small quantities through the passage 23 to the down pipe 6. 80 For the purpose of controlling the movements of the valve 16 I have provided mechanism generally indicated at 25 and which is connected with the valve chamber 16 by a stem 26. Cooperating with this stem is 85 a weighted lever 27, the weight 28 of which is adjustable to vary its influence upon the valve. Above the weighted lever 27 is a cylinder 29 supported upon suitable supporting means 30 and in the cylinder a 90 piston 31 is reciprocable. The piston is connected to the rod 26 and moves up and down with the rod, being normally held in bottom position, i. e., with the valve closed, by action of the weight 28 and by a spring 32 95 whose pressure is variable by means of an adjustable follower 33. A connection 34 extends between the space below the piston 31 in the cylinder 29 and the pipe 6 beyond the casing 11. A bypass 35 controlled by a 100 valve 36 is arranged so as to permit air to pass around the automatic controlling means if desired, this being usable if the automatic means gets out of order, for example.

From the foregoing description the mode 105 of operation of this mechanism will be, it is thought, readily apparent. It will be observed that by reason of the action of the dual loading means for the valve 16 a certain pressure must exist in the line 6 before the 110

2
 valve will be unseated and that relatively small variations in the pressure in the line 6 will make fairly substantial changes in the position of the valve 16 by reason of the fact 5 that the compression of the relatively light spring 32 will be the only additional work necessary in the upward movement of the valve. Now bearing in mind the fact that the pressure in the pipe 6 is substantially 10 that of the pressure in the foot piece 7, making allowances for some reduction due to friction in the pipe line, etc., it will be noted that when the liquid level in the chamber 10 varies, the pressure in the pipe line 6 will 15 vary. This fact is made use of to effect the automatic control referred to. Assume that the liquid level is so low that the valve 16 is closed; the conditions will then be that a small quantity of air is passing through the 20 passage 23 and down the line 6 and bubbling up through the riser pipe 8 but at such a rate as to produce no pumping. Now assume that the liquid level rises in the chamber 10. This will result in the pressure building up slightly 25 in the line 6 and if the liquid level rises sufficiently the pressure will rise to a sufficient degree so that the pressure passing through the port 34 will raise the piston 31 and so the valve 16, and pumping will begin. 30 Still bearing in mind that the pressure in the line 6 will closely follow that in the foot piece 7 and that the latter will vary with the hydrostatic head, it will be evident that, if the level continues to rise in the well due 35 to considerable liquid being supplied thereto, the pressure transmitted through the pipe line 24 will increase and the valve 16 will open wider, thereby opening additional ports 21 and 22. It will be obvious that if the inflow 40 to the chamber 10 falls off, the liquid level will be reduced and so the valve will progressively move toward closed position and finally close if the level is sufficiently reduced. It will thus be clear that I have provided 45 means for automatically controlling the operation of the pumping mechanism. One useful result of the provision of the bleeder 23 is that the level in the well or sump 10 cannot rise excessively due to leakage in the pipe 6 preventing rise in pressure 50 below the piston 31.

While I have in this application specifically described one form which my invention may assume in practice, it will be understood 55 that this form of the same is shown for purposes of illustration and that the invention may be modified and embodied in other forms without departing from its spirit or the scope of the appended claims.

60 What I claim as new and desire to secure by Letters Patent is:

1. In an air lift pumping mechanism, a source of pumping fluid, a foot piece, and means connecting the same including means always in communication with the fluid flow

to said foot piece for varying the communication between them in proportion to the variations in the hydrostatic head against which pumping fluid is discharged, said connecting means being adapted to allow a 70 flow of fluid which is insufficient to pump a normal flow of fluid under any head thereof during the existence of normal pumping pressure.

2. In a controlling mechanism for an air 75 lift pumping mechanism which comprises a source of pumping fluid and a pumping mechanism operated thereby, a controlling valve, and means for loading said valve including a fixed load tending to close said valve to thereby substantially limit fluid flow to said pumping mechanism and a load which increases upon movement of the valve.

3. In a controlling mechanism for an air 80 lift pumping mechanism which comprises a source of pumping fluid and a pumping mechanism operated thereby, a controlling valve, and means for loading said valve including a fixed load tending to close said valve to thereby substantially limit fluid flow to said pumping mechanism and a load which increases upon movement of the valve, said last mentioned means including means 85 for varying said second mentioned load.

4. In a controlling mechanism for an air 90 lift pumping mechanism which comprises a source of pumping fluid and a pumping mechanism operated thereby, a controlling valve always under the influence of fluid flowing to said pumping mechanism for allowing a minimum flow of fluid thereto insufficient to pump fluid at a normal rate during normal pressure at said source, and means for loading said valve including a 95 fixed load and a load which increases upon movement of the valve, said last mentioned means including means for changing said first mentioned load.

5. In a controlling mechanism for an air 100 lift pumping mechanism which comprises a source of pumping fluid and a pumping mechanism operated thereby, a controlling valve, and means for loading said valve including a fixed load and a load which increases upon movement of the valve, said last mentioned means including means for varying 105 independently both of said loads.

6. In a controlling mechanism for an air 110 lift pumping system comprising a source of fluid pressure and a foot piece supplied thereby, a valve mechanism always in communication with the actuating fluid flowing to said foot piece, and means whereby said valve mechanism automatically controls said supply in accordance with variations in head 115 against which said foot piece discharges comprising a valve casing having a plurality of perforations and a valve movable to vary the number of open perforations, said valve mechanism being adapted to allow a flow of 120

fluid which is insufficient to pump a normal flow of fluid under any head thereof during the existence of normal pumping pressure.

7. In a controlling mechanism for an air lift pumping system comprising a source of fluid pressure and a foot piece supplied thereby, a valve mechanism for automatically controlling said supply in accordance with variations in head against which said foot piece discharges comprising a valve casing having a plurality of perforations and a valve movable to vary the number of open perforations, said valve mechanism always being in communication with the actuating fluid flowing to said foot piece and comprising means for permitting a constant fluid supply in excess of a predetermined minimum to said foot piece and adapted to allow a flow of fluid which is insufficient to pump a normal flow of fluid under any head thereof during the existence of normal pumping pressure.
8. In a controlling mechanism for an air lift pumping system comprising a source of fluid pressure and a foot piece supplied thereby, a valve mechanism for automatically controlling said supply in accordance with variations in head against which said foot piece discharges comprising a valve casing having a plurality of perforations and a

valve movable to vary the number of open perforations, said valve being traversed by a leak port so disposed as to open communication between the source of fluid pressure and the foot piece when said valve is closed. 35

9. In a controlling mechanism for an air lift pumping system comprising a source of fluid pressure and a foot piece supplied thereby, a valve mechanism for automatically controlling said supply in accordance 40 with variations in head against which said foot piece discharges comprising a controlling valve and actuating means therefor including a member subjected to a pressure which increases equally with the hydrostatic head of the liquid surrounding the foot piece, and a bypass around said valve mechanism to allow a full flow of fluid from said source to said foot piece. 45

10. In an air lift pumping mechanism, a 50 source of pressure fluid, a foot piece, means for connecting the same, means for controlling fluid flow to said foot piece automatically responsive to variations in the head of the liquid pumped, and a manually controlled 55 bypass around said valve mechanism adapted to allow a full flow of actuating fluid to said foot piece.

In testimony whereof I affix my signature.
CHARLES BRAND OFFICER.
